(57) **CLAIM**

The ornamental design for a vibration sensor case, as shown and described.

DESCRIPTION

FIG. 1 is a front and right perspective view of a vibration sensor case, showing our new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an enlarged cross-sectional view taken along the line 8-8 in FIG. 2; and,

FIG. 9 is an enlarged cross-sectional view taken along the line 9-9 in FIG. 4.
